[57] CLAIM

The ornamental design for a combined leg and foot guard for protection when using a line trimmer, as shown and described.

DESCRIPTION

FIG. 1 is a right side perspective view of a combined leg and foot guard for protection when using a line trimmer showing my new design, the leg shown in broken lines is for illustrative purposes only and forms no part of the claimed design;

FIG. 2 is a left side perspective view thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a left side perspective view thereof.
